GAME BOARD

Elizabeth H. Burckes, Sudbury, Mass.

Application April 13, 1953, Serial No. 24,458

Term of patent 14 years

(Cl. D34—5)

To all whom it may concern:

Be it known that I, Elizabeth H. Burckes, a citizen of the United States and residing at Sudbury, Massachusetts, have invented a new, original, and ornamental Design for a Game Board, of which the following is a specification, reference being had to the accompanying drawing, forming part thereof.

The figure is a plan view of a game board, showing my new design. The game board is of conventional thickness.

I claim:

The ornamental design for a game board, as shown and described.

ELIZABETH H. BURCKES.
